Hardware Age, 9/1/69, p. 49-Dymo Precision Pricer.

[73] Assignee: Kabushiki Kaisha Sato, Japan

Primary Examiner—Louis S. Zarfas
Attorney, Agent, or Firm—Ostrolenk, Faber, Gerb & Soffen

[**] Term: 14 Years

[57] CLAIM

[21] Appl. No.: 385,767

The ornamental design for a hand operated label applying machine, as shown.

[22] Filed: Jun. 7, 1982

DESCRIPTION

[30] **Foreign Application Priority Data**
Dec. 8, 1981 [JP] Japan 56-54272
[52] **U.S. Cl.** D18/19
[58] **Field of Search** D18/13-15,
D18/18, 19, 22, 99; D19/68; D8/49, 50;
101/288; 156/384, DIG. 48, DIG. 49

FIG. 1 is a left side elevational view of a hand operated label applying machine showing our new design;
FIG. 2 is a right side elevational view thereof;
FIG. 3 is a top plan view thereof;
FIG. 4 is a bottom plan view thereof;
FIG. 5 is a front view thereof;
FIG. 6 is a rear view thereof;
FIG. 7 is an elevational cross-sectional view thereof;
and
FIG. 8 is a left side perspective view thereof.
